DESIGN FOR A LINE GUIDE FOR FISHING RODS

Louis Tengel, Geneva, Ohio, assignor to The
American Fork & Hoe Company, Cleveland,
Ohio, a corporation of Ohio

Application October 13, 1939, Serial No. 87,646

Term of patent 14 years

To all whom it may concern:

Be it known that I, Louis Tengel, a citizen of the United States, residing at Geneva, in the county of Ashtabula and State of Ohio, have invented a new, original, and ornamental Design for Line Guides for Fishing Rods, of which the following is a specification, reference being had to the accompanying drawing, forming a part hereof, in which:

Fig. 1 is a perspective view of the line guide showing my new design, and
Fig. 2 is a side view thereof.

I claim:

The ornamental design for a line guide for fishing rods, substantially as shown.

LOUIS TENGEL.
